RADIO PROGRAM HOLDER

George W. Leyen, Denver, Colo.

Application January 24, 1936, Serial No. 60,698

2 Claims. (Cl. 40—82)

The invention relates to a portable holder and more especially to a radio program holder.

The primary object of the invention is the provision of a holder of this character, wherein a program to be rendered through radio broadcasting stations may be placed in a convenient position for a listener-in and which will facilitate the fastening of the display strip containing the programs as the numbers thereon are rendered.

Another object of the invention is the provision of a holder of this character, wherein the construction thereof is of simple form and a strip bearing radio programs may be conveniently displayed and under adjustment of such strip a particular program may be brought to view.

A further object of the invention is the provision of a holder of this character, which is simple in its makeup, neat in appearance, thoroughly reliable and efficient in its operation, the program strip being readily and easily manipulated and a selected program in full view, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a front elevation of the holder constructed in accordance with the invention.

Figure 2 is a side view thereof the same being partly broken away.

Figure 3 is a rear elevation.

Figure 4 is a sectional view on the line 4—4 of Figure 1 looking in the direction of the arrows.

Figure 5 is a sectional view on the line 5—5 of Figure 2 looking in the direction of the arrows.

Figure 6 is a sectional view on the line 6—6 of Figure 1 looking in the direction of the arrows.

Similar reference characters indicate corresponding parts throughout the several views in the drawing.

Referring to the drawing in detail, the holder comprises a body 10 which may be made from any suitable material, having a flared base 11, the body being upwardly tapered and is of hollow formation closed at the upper smaller end and open at the bottom larger end. The open larger end of the body is constructed to accommodate a spool or reel 12 on which is manually wound a strip 13 carrying indicia making up a radio program or programs for display. The spool or reel 12 is releasably held engaged with spring tension

trunnions 14, these being slidably fitted in barrels 15 built within opposite ends of the body 10 and carry the springs 16 which releasably force the trunnions 12 into engagement with the spool or reel and in this manner the strip roll is supported within the body.

The body 10 at its front 17 has formed therein next to the open bottom the slot 18 through which is adapted to be trained the strip 13 so that it will traverse the outer flat face of the 10 said front 17 and is trained over a rounded top 19 provided at the upper smaller end of said body and thence trained downwardly at the rear of the body and loosely engaged in a retaining loop 20 provided at the back of the said body. 15 The free end of the strip 13 can be manually gripped for the feeding of the said strip to alter the display of a radio program matter present on the outer face of the strip at the front of the body.

Adapted to be located at the front 17 of the body 10 is a window sash 21 having a transparent panel 22 through which is rendered visible the indicia on the strip 13 as trained over the front 17 of the body 10. This sash 21 carries 25 a head flange 23 which overhangs the rounded top 19 and is provided with sockets 24 for accommodating dowel pins 25 made fast in the rounded top 19 while the bottom end of this sash 21 carries the dowel pins 26 releasably engaged in suitable sockets as provided in the base 11 of the body 10 and in this manner the sash is detachably secured in place. The strip 13 travels over the front 17 between it and the sash 21.

Loosely engaged with the trunnions 14 are the arms 27 of a tensioning bail 28 which plays upon the roll of the strip 13 for frictionally holding the same but allowing the feed of the strip on manual manipulation thereof for the changing of the displayed program appearing through the panel 22 in the sash 21 of the device.

It is intended that the radio programs for an entire week which are generally published in newspapers in strip order may be clipped from 45 the newspaper and rolled upon the spool or reel 12 and such strip move successively as the programs are completed so as to bring succeeding numbers and programs into view, these being made visible through the transparent panel 22 in 50 the sash 21 at the front of the body. The strip 13 can be readily detached from the spool or reel for substituting another strip in its place.

The radio programs to be used in the holder constituting the present invention is a specially 55

prepared strip now called "The Weekly Strip of the Air" and is issued weekly. This program will be issued in spool form and will show N. B. C., C. B. S. and World B. C. programs and 5 such programs will vary according to the localities they will be issued in. For instance: The type program issued in El Paso will show N. B. C., C. B. S. and World B. C. programs as well as interesting numbers from Dallas, San Antonio, 10 etc. Los Angeles programs would take in a section covering San Diego to the south and San Francisco to the north.

What is claimed is:

1. A device of the character described comprising a body of tapered formation and having a slot in its front close to the bottom thereof, a rolled strip supported in the body and trained through the slot to traverse the front of said body and over the top of the latter, a transparent paneled sash fitting over the front of the 15

body for rendering visible said strip, tensioning means frictionally engaging the rolled strip within the body and a head extension on the sash to overhang the top of the body and guiding the strip rearwardly of the latter. 5

2. A device of the character described comprising a body of tapered formation and having a slot in its front close to the bottom thereof, a rolled strip supported in the body and trained through the slot to traverse the front of said 10 body and over the top of the latter, a transparent paneled sash fitting over the front of the body for rendering visible said strip, tensioning means frictionally engaging the rolled strip within the body, a head extension on the sash to 15 overhang the top of the body and guiding the strip rearwardly of the latter and a loop at the back of the body for receiving the free end of the strip.

GEORGE W. LEYEN. 20
